UNITED STATES PATENT OFFICE.

JUSTIN R. DORAN, OF BEAVER, IOWA.

ARMOR FOR SOLDIERS.

1,212,463.

Specification of Letters Patent. Patented Jan. 16, 1917.

Application filed July 31, 1916. Serial No. 112,423.

To all whom it may concern:

Be it known that I, JUSTIN R. DORAN, a citizen of the United States, and resident of Beaver, in the county of Boone and State of Iowa, have invented a certain new and useful Armor for Soldiers, of which the following is a specification.

The object of my invention is to provide an armor for soldiers of simple, durable and inexpensive construction.

A further object is to provide an armor for soldiers so constructed and arranged that the armor may be readily and easily supported and carried by the soldier for protecting him when in battle.

Still a further object is to provide such an armor which may be readily and easily adjusted and supported on the ground in position for protecting the soldier when lying on the ground.

A further object is to provide an armor of the kind mentioned, preferably made of two plates so connected and arranged with their side edges adjacent to each other, to form a single large plate, or by simple adjustment of the parts they may be connected so as to have in horizontal cross section the form of a V.

My invention consists in the construction, arrangement and combination of the various parts of the device whereby the objects contemplated are attained, as hereinafter more fully set forth, pointed out in my claims, and illustrated in the accompanying drawings in which:—

Figure 1 shows a front elevation of an armor for soldiers embodying my invention. Fig. 2 shows a rear elevation of the same. Fig. 3 shows a top or plan view of the same, partly in section, the dotted lines showing the position of one of the plates when arranged at an angle to the other plate. Fig. 4 shows a side elevation of my improved armor when installed on the ground. Fig. 5 shows a detail, sectional view taken on the line 5—5 of Fig. 4. Fig. 6 shows a sectional view taken on the line 6—6 of Fig. 2. Fig. 7 shows a detail, sectional view illustrating the method of fastening the two large plates together. Fig. 8 shows a side elevation of a soldier equipped with one of my improved armors, and Fig. 9 shows a perspective view of several of the armors arranged side by side on the ground with the soldier lying behind them.

In the exemplification of my invention

illustrated in the accompanying drawings, I have shown my armor comprised of two comparatively large sheets of metal which I have indicated in the accompanying drawings by the reference characters 10 and 11. Secured to the top and bottom edges of the members 11 are strips of resilient metal 12 which project considerably beyond the side edge of the member 11 as shown in Figs. 1 and 2. At each end of each plate 10 adjacent to the same side edge thereof is a channel-shaped member 13 having the ends of the member 10 received between its walls. The central part of each channel-shaped member 13 is spaced from the adjacent edge of the member 10. The projecting portions of the strips 12 are extended through the channel-shaped members 13 between the central parts thereof and the edges of the plate 10. The extreme free ends of the strips 12 project beyond the members 13 extending outwardly from the top and bottom edges of the plate 10. Within the channel-shaped members 13 are pins 14 projecting from the end of the plate 10. Each strip 12 is provided with an opening 15 adapted to receive one of the pins 14.

In assembling the plates 10 and 11 together, the free ends of the strips 12 are drawn outwardly from the plate 10 to permit them to pass over the pins 14, until the holes 15 register with the pins 14. The strips 12 are then released, and their resiliency will cause them to move to position adjacent to the end edges of the plates 10, with the pins 14 received in the holes 15.

The strips 12 are of proper width to fit between the walls of the channel-shaped members 13 whereby the plates 10 and 11 are held against twisting movement with relation to each other, and are caused to form a continuous flat plate. Formed in the opposite wall of each channel-shaped member 13 are openings 16 and 17. These openings are arranged diagonally across the plate 10 from each other, as clearly shown in Fig. 3.

The walls of the channel-shaped members 13, at the sides of the openings 16 and 17, are beveled so that when desired the strips 12 may be inserted through the openings 16 and 17, as illustrated by dotted lines in Fig. 3, and when so inserted will be held against any horizontal swinging movement.

The openings 16 and 17 are of such height as to permit the raising and lowering of the strips 12, so that said strips may be raised

or drawn away from the end edges of the plate 10 to permit the strips to clear the pins 14, during the assembling and dissembling of the plates 10 and 11. Each plate 5 11 is provided with an opening 18 through which a rifle may be extended.

Pivoted at a point above each opening 18 is a cover plate 19 adapted normally to drop by gravity to position for covering the 10 opening 18 with its edges overlapping the portion surrounding the opening 18. Each plate 19 is provided with an inwardly extending lug 20 projecting into the adjacent opening 18 and adapted to limit the swinging 15 movement of the cover plate 19.

Secured to the inner surface of each plate 10 and 11 near the upper end thereof is a loop 21 through which a strap 22 or the like may be secured for supporting my improved armor on a soldier.

Secured to the inner surface of each plate 11 adjacent to and projecting beyond the side edge thereof opposite the plate 10, are keeper members 23. Secured to the outer 25 surface of each plate 11, parallel with each keeper member 23, is a similar keeper member 24. It will be seen that where it is desired to place several members of my armor edge to edge, the members 23 and 24 will receive 30 between them the adjacent edge of the next member 10, of the armor.

Secured to the inner surface of each plate 10 and 11 near the lower end thereof and near the outer edge thereof is a loop 25 to 35 which may be secured a strap 26 designed to go around the waist of a soldier, as shown in Fig. 8.

Pivoted secured to the inner surface of each plate 10 and 11 preferably somewhat 40 near the upper end thereof, is a supporting brace member 27, having the short points 28 at its free end, as shown by dotted lines in Fig. 2.

A substantially rectangular strip 29 is 45 centrally pivoted to the lower or pointed end of each brace 27. As a matter of fact each strip 29 is pivoted just enough off center so it will normally hang by gravity with one end down, as shown by the full lines in 50 Fig. 2, to position to cover the point 28, of the brace 27.

Slidably mounted on the brace 27 above the pivot point of the strip 29 is a loop 30. The loop 30 may be used to hold the strip 55 29 parallel with the brace 27 as shown by full lines in Fig. 2, when the brace hangs downwardly adjacent to the plates 10 and 11. When, however, it is desired to install my improved armor on the ground, as 60 shown in Fig. 4, where the plates 10 and 11 are inclined upwardly and rearwardly, then the braces 27 are extended rearwardly and downwardly as shown in said figure, and the loops 30 are pushed upwardly on the brace 27, and the strips 29 are moved to

horizontal position where they tend to limit the distance. The sharp ends of the brace 27 may be forced downwardly into the ground. The loops 30 are allowed to drop adjacent to the strip 29 and tend to hold 70 them in their horizontal position.

Secured to the inner surface of the plates 10 by any suitable attachment, near the side edge thereof opposite the plate 11 to which said plate is then secured, is a hook 31. On 75 the plate 11, on the inner surface thereof is a button 32 adapted to coat with the hook 31 of the adjacent plate 10. Two of my armors are placed end to end.

In the practical use of my improved armor, it may be put to a great variety of uses. By extending the strips 12 through the openings 16 and 17, the plates 10 and 11 may be arranged at an obtuse angle to each other in convenient form for wearing the armor, as illustrated in Fig. 8. It is, of course, obvious that the armor in this form may be placed on the ground and supported by the braces 27. When desired, the plates 10 and 11 may be assembled as shown in 90 Fig. 2 forming substantially one large plate and the armor may be placed on the ground as illustrated in Fig. 4 and supported by means of the braces 27. When the armor is carried by the soldier the members 29 are 95 placed in position parallel with the braces 27 and the loops 30 are extended thereover holding said member 29 in position. When the pointed ends of the braces 27 are sunk into the ground the loops 30 are moved upwardly and the members 29 are moved to horizontal position whereupon the loops 30 are moved downwardly to their position shown in Fig. 2 where they will hold the members 29 in their horizontal position for 100 the purpose of limiting the distance which the sharp ends of the brace 27 can be forced into the ground.

A plurality of my armors may be placed edge to edge for protecting a number of soldiers, as shown in Fig. 9. When the armors are so used, the free side edges of the plate 10 are slipped between the members 23 and 24 of the adjacent plate 11 of the next armor.

The armors may be locked in series by securing the hooks 31 to the button 32 of the next adjacent armor.

The rifle man can push the pivoted member 19 aside by means of the lug 20 and insert his rifle through the opening 18. As soon as the rifle is removed, the member 19 will automatically drop to position for covering the opening 18.

The straps 22 may be extended around the body of the wearer, as shown in Fig. 8, and the straps 26 can be extended around the waist. The armor can be carried in such position as to protect the chest and the abdomen of the soldier. The straps 22 may 125

3

be very quickly and easily installed by simply doubling over one end of the strap, after the strap has once been inserted through one of the loops 21 and then slipping the 5 doubled over end through said loop as shown in Fig. 6.

Some changes may be made in the construction and arrangement of the various parts of my improved armor without 10 parting from the essential features and purposes thereof, and it is my intention to cover by this application any modifications of structure and any mechanical equivalents, which may be included within the reasonable 15 scope of my claims:

I claim as my invention:

1. An armor comprised of two sheets of suitable metal placed edge to edge, and means for locking said sheets together, and 20 adapted to hold said sheets locked in alignment with each other, or in position forming an obtuse angle with relation to each other.

2. An armor comprising a pair of plates 25 adapted to be arranged with their side edges adjacent to each other, a strip on each end of one of said plates projecting beyond the side edge thereof made of resilient material, a receiving member on each end of the other 30 plate adapted to receive the projecting end of one of said strips of said first plate, the projecting ends of said strips and the ends of the adjacent plate having coacting means for locking said plates together.

3. An armor comprising a pair of plates, adapted to be arranged with the side edge of one plate adjacent to the side edge of the other plate, strips of resilient material secured to the ends of one plate and projecting 40 beyond the side edge thereof, channel-shaped members mounted on the end of the other plate near the side edge thereof adjacent to the first plate with the ends of the strips of said first plate received within the walls of 45 said channel-shaped member, with the central portions of the channel-shaped members spaced from the end of said plate to which the end of said channel-shaped members are secured, said channel-shaped member being 50 adapted to receive the projecting ends of said resilient strip, said projecting end and the end of said second plate being provided with coacting locking means.

4. An armor comprising a pair of plates 55 adapted to be arranged with the side edge of one plate adjacent to the side edge of the other plate, strips of resilient material secured to the ends of one plate and projecting beyond the side edge thereof, channel- 60 shaped members mounted on the end of the other plate near the side edge thereof adjacent to the first plate with the ends of the strips of the first plate received within the walls of said channel-shaped members, with 65 the central members of the channel-shaped

portions spaced from the end of said plate to which the end of said channel-shaped member is secured, said channel-shaped member being adapted to receive the projecting ends of said resilient strip, said projecting ends and the ends of said second plate being provided with coacting locking means, as to be within the channel-shaped members when the plates are assembled and locked together. 70

5. An armor comprising a pair of plates, adapted to be arranged with the side edge of one plate adjacent to the side edge of the other plate, strips of resilient material secured to the ends of one plate and projecting beyond the side edge thereof, channel-shaped members mounted on the end of the other plate near the side edge thereof adjacent to the first plate with the ends of said strips of the first plate received within the walls of said channel-shaped member, with the central portions of said channel-shaped member spaced from the end of said plate to which the end of said channel-shaped member is secured, said channel-shaped member being adapted to receive the projecting ends of said resilient strip, said projecting ends and the ends of said second plate being provided with coacting locking means, 80 each of said channel-shaped members having in its side wall spaced from the ends of the second plate, diagonally aligned openings adapted to receive the projecting ends of said resilient strips for permitting said plates to be locked together at obtuse 85 angles with relation to each other. 90

6. An armor comprising a pair of plates adapted to be arranged with the side edge of one plate adjacent to the side edge of the other plate, strips of resilient material secured to the ends of one plate and projecting beyond the side edge thereof, channel-shaped members mounted on the ends of the other plate near the side edge thereof adjacent to the first plate with the ends of the 105 strips of the first plate received within the walls of said channel-shaped member, with the central portions of the channel-shaped members spaced from the end of said plate to which the said channel-shaped member 110 is secured, said channel-shaped members being adapted to receive the projecting ends of said resilient strips, said projecting ends and the ends of said second plate being provided with coacting locking means, a 115 brace member pivoted to each of said plates. 120

7. An armor comprising a pair of plates adapted to be arranged with the side edge of one plate adjacent to the side edge of the other plate, strips of resilient material secured to the ends of one plate and projecting beyond the side edge thereof, channel-shaped members mounted on the ends of the other plate near the side edge thereof adjacent to the first plate with the ends of the 125 130

strips of the first plate received within the walls of said channel-shaped member, with the central portions of the channel-shaped members spaced from the ends of said plate 5 to which said channel-shaped members are secured, said channel-shaped members being adapted to receive the projecting ends of said resilient strips, said projecting ends and the ends of said second plate being provided with coacting locking means, a brace member pivoted to each of said plates, having a sharp free end, a bar pivoted to said brace member near its free end and adapted to be pulled from parallel position with the brace 10 member to position at substantially right angles thereto, and a loop slidably mounted on each brace member and adapted in one position to receive said bar for holding the 15 bar in position parallel with the brace member. 20

8. An armor comprising a plate, a brace member pivoted thereto, a bar pivotally mounted on said brace member near its free end and adapted to move from position parallel with said brace member to position extending transversely across the brace member, and a loop slidably mounted on the brace member adapted in one of said positions of said bar to receive the bar for holding it parallel to the brace member, and in 25 the transverse position of said bar to slide down on the brace for holding the bar in its transverse position. 30

Des Moines, Iowa, July 18, 1916.
